UNITED STATES PATENT OFFICE

161,339

DOLL

Patricia J. Hueter, Seattle, Wash.

Application August 15, 1949, Serial No. 4,508

Term of patent 3½ years

(Cl. D34—4)

To all whom it may concern:

Be it known that I, Patricia J. Hueter, a citizen of the United States, and a resident of Seattle, in the county of King and the State of Washington, have invented a new, original, and ornamental Design for a Doll, of which the following is a specification, reference being had to the accompanying drawings, forming a part thereof.

In said drawings:

Fig. 2 is a side elevational view thereof; and
Fig. 3 is a rear elevational view.

What I claim is:

The ornamental design for a doll, as described and shown.

PATRICIA J. HUETER.
